4 Claims. (Cl. 307—88.5)

This invention relates to linear sweep circuits capable of high speed and high repetition rates and particularly to sweep circuits of the bootstrap type.

Known bootstrap circuits operate by charging a sweep capacitor through a resistor which forms an RC-circuit therewith, and correcting the non-linear exponential charging voltage which prevails across the sweep capacitor. In particular, the increasing voltage across the charging sweep capacitor is sensed by an amplifier, preferably an emitter-follower type amplifier, and is applied across the entire RC-circuit by means of a feedback capacitor. The latter increases the potential across the RC-circuit in step with the rising voltage across the sweep capacitor, thereby forcing the sweep capacitor to continue charging at its initial charge rate. The voltage across the charging resistor then is comparatively constant and the voltage change across the sweep capacitor is comparatively linear.

While known bootstrap circuits improve sweep linearity, the latter depends upon the capacitance of the feedback capacitor being sufficiently high. However, the feedback capacitor must be recharged between sweep cycles and its charging rate is dependent partly upon the value of its capacitance. Thus improving the sweep linearity by increasing the capacitance of the feedback capacitor merely results in an increase of the necessary time delay between sweep cycles, thereby reducing the available repetition rate of the device or it results in a sweep time less than specified. For the above reasons, in existing bootstrap circuits the attainable linearity and repetition rate are limited by each other.

It is an object of the present invention to improve the linearity of the charging rate and hence the output of bootstrap circuits while nevertheless permitting a high repetition rate for individual sweeps, particularly sweeps of specified time duration and amplitude.

According to a feature of our invention we charge the feedback capacitor of a bootstrap sweep circuit by means of a separate low-impedance switch connected to the input signals initiating the sweep cycles rather than permitting the feedback capacitor to be charged, as they normally are, by the higher associated resistances of the amplifier which slow the charge time of this capacitor.

The various features of novelty characterizing the invention are pointed out in the claims forming a part of this specification. For a more complete understanding of the invention, its other objects and advantages, reference may be had to the following description when read in light of the drawings wherein:

FIG. 1 is a bootstrap circuit embodying features of the present invention, and FIG. 2 is a series of time-voltage curves *a*, *b*, *c*, and *d* of various portions of the circuit in FIG. 1.

In FIG. 1 a sweep capacitor *C*₁ is shunted by a switching transistor *G*₁ which is open when a zero or positive voltage is applied to its base by an input terminal *S*. A charging resistor *R*₁, connected to a voltage source *—Ecc* by means of a clamping diode *D*, charges the capacitor *C*₁ when the switching transistor *G*₁ is non-conductive. The base of a transistor amplifier *A*₁ senses the voltage at the upper plate of capacitor *C*₁. The collector of amplifier *A*₁ is connected to the voltage source *—Ecc* in emitter-follower fashion. The emitter output of the amplifier *A*₁ is connected by a feedback

2

capacitor *C*₂ to the junction of resistor *R*₁ and diode *D* so that the voltage across the capacitor *C*₁ is fed back to the resistor *R*₁ by means of the capacitor *C*₂. A transistor emitter-follower amplifier *A*₂ having an emitter resistor *RL* provides a high impedance output for the voltage at the emitter of amplifier *A*₁, which voltage corresponds to the voltage across capacitor *C*₁. An output terminal *L* connects to the emitter of transistor *A*₂. Connecting the input terminal *S* to the emitter of amplifier *A*₁ is an emitter-grounded switching transistor *G*₂. The latter charges the capacitor *C*₂ when a negative signal is applied to the terminal *S*.

Assuming that the transistor *G*₂ is disconnected the circuit operates as follows. When an input signal corresponding to that shown in FIG. 2*a* is applied to the terminal *S*, the sweep output depicted in FIG. 2*c* appears at the terminal *L*. Before the onset of the first negative pulse at terminal *S*, the switching transistor *G*₁ is non-conductive and capacitor *C*₁ has been charged to the to the lever *—Ecc* through the resistor *R*₁ and diode *D*. Thus transistor *A*₁ having its base at a negative level is normally conductive thereby applying to the capacitor *C*₂ by means of its emitter a negative voltage approaching *—Ecc*. Amplifier *A*₁ is thus normally conductive. Similarly, amplifier *A*₂ is normally conductive producing an output at the terminal *L* having the approximate value *—Ecc*. At the onset of the first negative pulse the switch *G*₁ becomes conductive thereby shunting and discharging the capacitor *C*₁. This renders the amplifier *A*₁ less conductive so as to make its emitter potential more positive thereby charging capacitor *C*₂ through diode *D* to the level *—Ecc*. This occurs during the interval marked *trs* in FIG. 2*a* and is shown in FIG. 2*c*.

At the end of pulse *trs* the voltage at terminal *S* returns to its initial value thereby rendering switch *G*₂ non-conductive. The capacitor *C*₁ is now free to charge again at a rate determined by the resistances of resistor *R*₁ and the forward resistance of diode *D* as well as the voltage *—Ecc*. At the first instance of charging the voltage change at capacitor *C*₁ is amplified by transistor *A*₁ and fed back to the junction of resistor *R*₁ and diode *D* by the capacitor *C*₂. Since the capacitor upper plate of capacitor *C*₁ has then become more negative, the voltage at resistor *R*₁ also becomes more negative, the amplifier *A*₁ and capacitor *C*₂ constituting a positive feedback. The more negative voltage at resistor *R*₁ will not cause a current leak through the diode *D* because of its high inverse resistance. The higher voltage at resistor *R*₁ maintains the rapidity of the initial charge rate so that the next increment of charge of capacitor *C*₁ is just as rapid thereby producing an even more negative potential at resistor *R*₁ and diode *D*. This feedback process continues as shown in FIG. 2*c* for the time *tsw*. The charge of capacitor *C*₁ and the output sweep cycle are specified to end at the onset of the next pulse *trs*. The linearity of the charge rate at capacitor *C*₁, and hence the linearity of the voltage at the base and emitter of amplifier *A*₂, is improved because the capacitor *C*₂ tends to maintain constant the voltage across resistor *R*₁.

The linearity of the output depends to a large extent on the capacitor *C*₂ having a comparatively high value. However, if the capacitance of condenser *C*₂ is increased, its charge rate through the associated resistances during the pulse *trs* will be slowed. The effect of such an increase is shown in FIG. 2*b*. It will be seen that the linearity of the sweep is markedly improved. However, the length and voltage variation of the sweep is also decreased below that specified.

According to the invention, we overcome this disadvantage by connecting an electronic switch *G*₂ between the terminal *S* and the emitter of amplifier *A*₁. Thus,

at the pulse t_{rs} , while capacitor C_1 is discharging, the capacitor C_2 is connected to ground by a transistor switch G_2 . The charge time of capacitor C_1 is considerably decreased, thus permitting the use of high capacitance to improve linearity without the detrimental effects usually associated therewith.

Now, despite a high capacitance C_2 the capacitor C_2 charges rapidly during the pulse t_{rs} . At the end of pulse t_{rs} and beginning of the sweep cycle t_{sw} switch G_2 is opened and the increased capacitance C_2 provides the linear sweep shown in FIG. 2d.

During the sweep time, the emitter voltage of the transistor A_1 reaches a point corresponding to the charging voltage of the capacitor C_1 , the diode D is blocked, and the charge in the capacitor C_2 is discharged through the resistor R_1 and charges the capacitor C_1 .

The diode D is connected with its cathode connected to the voltage source $-E_{cc}$ and with its anode connected to the resistor R_1 and to the capacitor C_2 . The diode D functions to charge the capacitor C_2 to $-E_{cc}$ during the time that the switch G_2 is conductive.

When the switch G_2 is non-conductive, the diode D is blocked, due to the emitter voltage of the transistor A_1 becoming negative, and the capacitor C_2 discharges through the resistor R_1 to charge the capacitor C_1 .

While an embodiment of the invention has been shown in detail, it will be obvious to those skilled in the art that the invention may be practiced otherwise without departing from its scope and spirit.

We claim:

1. A high speed linear sweep circuit, comprising a sweep capacitor, first switch means connected across said sweep capacitor for discharging said sweep capacitor and for permitting said sweep capacitor to charge through said first switch means, a charging resistor connected to said sweep capacitor, amplifier means having an input connected to said sweep capacitor and an output and responding to the voltage across said sweep capacitor, a voltage source, a clamp diode connected to said charging resistor and adapted to connect said charging resistor to said voltage source, a clamp capacitor connecting the junction of said diode and said charging resistor to the output of said amplifier means, and second switch means responsive to an input signal for charging said clamp capacitor during discharge of said sweep capacitor, said second switch means being connected from the input of said first switch means to the output of said amplifier means.

2. A high speed linear sweep circuit as claimed in claim 1, wherein each of said first and second switch means comprises a transistor.

3. A high speed linear sweep circuit, comprising a sweep capacitor, a first transistor having emitter, collector and base electrodes and being adapted to be switched to one of a non-conducting condition and a conducting condition, means for applying input signals to the base electrode of said first transistor, means connecting said first transistor across said sweep capacitor for discharging said sweep capacitor and for permitting said sweep capacitor to charge in response to said input signals, a charging resistor connected to said sweep capacitor, amplifier means having an input connected to said sweep capacitor and an output and responding to the voltage across said sweep capacitor, a voltage source, a clamp diode connected to said charging resistor and adapted to connect said charging resistor to said voltage source, a clamp capacitor connecting the junction of said diode and said charging resistor to the output of said amplifier means, a second transistor having emitter, collector and base electrodes and being adapted to be switched to one of a non-conducting condition and a conducting condition, means connecting the base electrode of said second transistor to the base electrode of said first transistor, and means connecting the collector electrode of said second transistor to the output of said amplifier means, said second transistor being responsive to said input signals for charging said clamp capacitor during discharge of said sweep capacitor.

4. A high speed linear sweep circuit as claimed in claim 3, wherein said amplifier means comprises a third transistor having emitter, collector and base electrodes, the base electrode of said third transistor being connected to said sweep capacitor, the emitter electrode of said third transistor being connected to the collector electrode of said second transistor, and the collector electrode of said third transistor being connected to said voltage source.
